Inventor
HOWARD E. VAN ORDEN,

By his Attorneys Edgar Gates & Co.

UNITED STATES PATENT OFFICE.

HOWARD E. VAN ORDEN, OF EAST ORANGE, NEW JERSEY, ASSIGNOR OF ONE-HALF TO
JOSEPH W. SINNOTT, OF BROOKLYN, NEW YORK.

SLIDING DOOR.

1,173,399.

Specification of Letters Patent. Patented Feb. 29, 1916.

Application filed December 31, 1914. Serial No. 879,873.

To all whom it may concern:

Be it known that I, HOWARD E. VAN ORDEN, a citizen of the United States, and residing at East Orange, in the county of Essex and State of New Jersey, have invented certain new and useful Improvements in Sliding Doors, of which the following is a specification, such as will enable those skilled in the art to which it appertains to make and use the same.

This invention relates to sliding doors and particularly to combination doors of this class involving both swinging and sliding doors such as are usually employed in connection with elevators or elevator shafts, and which involve a swinging door member and one or more sliding door members which are adapted to be moved into a plane or planes adjacent to and parallel with the swinging door member, in which position all of said door members may be swung into an open position so as to fully open the door space whenever desired in order to permit large articles of any kind or class to be passed into and removed from the elevator; and the object of this invention is to provide improved means for manipulating or operating the sliding door member or members.

In the accompanying drawing I have shown my improvement applied to a door having but one sliding member, and the invention is fully disclosed in the following specification, of which the accompanying drawing forms a part, in which the separate parts of my improvement are designated by suitable reference characters in each of the views, and in which:

Figure 1 is an inside view of part of an elevator frame and showing the sliding door member in an open position; Fig. 2 a partial section on the line 2—2 of Fig. 1 and showing the hinged door member in a fully open position and showing the sliding door member in an open partially swung position and indicating the same in dotted lines in the fully swung position; Fig. 3 a section on the line 3—3 of Fig. 2; Fig. 4 a section on the line 4—4 of Fig. 2 and showing the parts in a different position from that shown in Fig. 3; and, Fig. 5 a section on the line 5—5 of Fig. 3, Figs. 3, 4 and 5 being on an enlarged scale.

In the drawing forming part of this specification, I have shown at *a* the right hand top portion of an elevator door frame and com-

prising a horizontal top member *a*², and a vertical side member *a*³. The top frame member *a*² is provided with the usual hanger slide bar *b*, and at *c* I have shown the swinging door member which is hinged to the frame member *a*³ in the usual manner at *c*², and at *d*, I have shown the sliding door member with the top of which is connected the hanger plate *e* one end of which is pivoted to the sliding door member *d* at *e*². The hanger slide bar *b* is provided with the usual hanger blocks *f* which are adjustable longitudinally thereon and with which are connected hanger bolts *f*² which are threaded and provided with top and bottom nuts *f*³ and *f*⁴ and the hanger plate *e* is secured to the blocks *f* by means of the bolts *f*², and all this construction is old and well known and forms no part of my invention.

In the practice of my invention, I secure on the free end portion of the hanger plate *e* an attaching block *g*, this connection being made by means of bolts *g*², and said attaching block is slotted longitudinally as shown at *g*³, and pivoted in the inner end portion of the slot in said block and centrally thereof is a lock pawl *h*. The head *h*² of the pawl *h* is provided with side trunnions *h*³ and a cap plate *g*⁴ is secured to the block *g*, and in connection with said block forms bearings for the trunnions *h*³, and said trunnions *h*³ are also provided with angular extensions *h*⁴ adapted to receive a key *i* indicated in dotted lines in Fig. 5, and by means of which the lock pawl *h* may be operated as hereinafter described.

The head *h*² of the lock pawl *h* is approximately circular in form and provided in its back face with socket recesses *h*⁵ and *h*⁶, and secured to the attaching block *g* or the top plate *g*⁴ thereof at *j* is a spring *k* provided with a lock pin *h*², and said spring and pin are adapted to lock the pawl *h* in the operative position shown in Fig. 3 and also in the inoperative position shown in Fig. 4. The pawl *h* is also provided at its free end with an angular nose piece *h*⁷ and the hanger plate *e* is provided with a longitudinal slot *e*³ through which said pawl operates, and the sliding door member *d* is provided in the top thereof and under the free end portion of the plate *e* with an angular recess *d*² in which is located an angular nose *m* adapted to receive the pawl *h* as shown in Fig. 1, and by means of this construction the hanger plate *e* is locked to

the door member *d* under ordinary conditions, and said door member is free to slide so as to open and close a part of the door space in the usual manner.

5 Under ordinary circumstances and when the door member *c* is in the closed position, the door member *d* may be slid back and forth so as to admit of ingress and egress to and from the elevator, and in this position 10 of said door members the hinged door *c* is on the outer side of the door member *d*.

When it is desired to use the entire door space the door member *c* is swung outwardly as shown in Fig. 2, and the door member *d* being slid into the position shown 15 in Fig. 1, the spring *k* is raised so as to free the lock pin *h*² from the socket recess *h*⁵ in the head of the pawl *h* and the key is applied to said pawl, as indicated in dotted lines in Fig. 5, and the pawl is turned into the inoperative position shown in Fig. 4, after which the door *d* may also be swung 20 fully in the open position as indicated in dotted lines in Fig. 2.

25 When it is desired to return the door members *d* and *c* to their normal position, the door member *d* is swung back under the hanger plate *e* and the pawl *h* is turned into the operative position as shown in Figs. 1 and 3 30 by means of the key *i*, and said door member is locked to the plate *e* and may be manipulated as a sliding door in the usual manner and the same as other doors of its class.

35 It must be understood that the door member *d* turns on a pivot or pivots which are not shown and described, but which are of the usual form and construction, and while I have shown and described my improvement 40 as applied to one sliding door member

used in connection with a swinging door, it will be understood that my improvement may be applied where a plurality of sliding door members are used in connection with a swinging door member, or the improvement may be applied, if desired, to a sliding door only, and while I have shown and described the preferred means for carrying my invention into effect the said invention is not limited to the details of construction 45 herein shown and described, and changes therein and modifications thereof may be made, within the scope of the appended claim, without departing from the spirit of my invention or sacrificing its advantages. 50

Having fully described my invention, what I claim as new and desire to secure by Letters Patent, is:—

A fastening means comprising a plate 60 provided with a slot, bearings provided on said plate, a pawl having trunnions which are mounted in said bearings, said pawl being provided with a plurality of recesses and being adapted to work in said slot, a key engaging portion provided on one of 65 said trunnions and adapted to be engaged by a key for operating said pawl, a spring mounted on said plate and provided with a pin for engaging said recesses for maintaining said pawl in locked or unlocked position, and an angular nose which is adapted to be engaged and disengaged by said pawl.

In testimony that I claim the foregoing as my invention I have signed my name in presence of the subscribing witnesses this 70 28th day of December, 1914.

HOWARD E. VAN ORDEN.
